UNITED STATES PATENT OFFICE.

AUGUST M. BECKER, OF TORONTO, ONTARIO, CANADA.

ROCK-DRILL.

1,183,827.

Specification of Letters Patent.

Patented May 16, 1916.

Application filed December 18, 1913. Serial No. 807,426.

To all whom it may concern:

Be it known that I, AUGUST M. BECKER, a citizen of the United States of America, and resident of the city of Toronto, county 5 of York, Province of Ontario, in the Dominion of Canada, have invented certain new and useful Improvements in Rock-Drills, as described in the following specification and illustrated in the accompanying 10 drawings, that form part of the same.

The principal objects of the invention are, to effect a saving of time and labor and to obviate many of the difficulties in manual rock drilling operations and to devise a 15 drilling rig which may be operated with ease and precision by one man and the work accomplished in a much more effective manner than by two men in the ordinary manner of manual drilling.

20 A further object is to provide a device which is very compact and may be easily carried from place to place, thus providing a device which is particularly adaptable to prospecting mining.

25 A still further object is to devise a rig which has great flexibility of adjustment and is of a simple and durable construction.

The principal feature of the invention 30 consists in the novel construction and arrangement of parts, whereby the drill is held in the desired position to be struck by the sledge and whereby it is rotated by the operator after each stroke of the hammer.

In the drawings, Figure 1 is a perspective view of the invention set up ready for 35 use. Fig. 2 is a plan view on a reduced scale. Fig. 3 is an enlarged perspective detail of the drill holding and ratchet rotating parts shown separated to disclose the 40 details of their construction.

Like numerals of reference indicate corresponding parts in each figure.

Referring to the drawings, 1 is a short bar here shown formed with flattened ends 2 to 45 which are pivotally secured the legs 3, said legs having pointed extremities to form a grip on the rock or place which is to be drilled.

4 is a yoke shaped member having the 50 collar ends 5 encircling the bar 1 and pivoted thereon.

6 is a leg extending outwardly from the yoke and forming a third leg support also preferably pointed at the end.

55 7 are weights secured to the legs 3 and 6

to hold the rig down to its position for operating.

8 is a longitudinally split sleeve encircling the rod 1 between the collars of the yoke 4 and adapted to be clamped thereon 60 in any desired position, suitable bolts 9 extending therethrough across the longitudinal slit.

10 is a semi-cylindrical member formed integral with the upper half of the split 65 sleeve 8 arranged centrally of its length having a central hole 11 therethrough and a central boss 12 around which are formed a plurality of ratchet teeth 13.

14 are dove tailed grooves formed in the 70 flat face 15 of the member 10 open at the top and tapering toward the bottom.

16 is a semi-cylindrical member of corresponding shape to the member 10 adapted to be fitted to the face 15 thereof and formed 75 with dove-tailed rib projections 17 adapted to fit the grooves 14. When the two semi-cylindrical portions are fitted together they present a cylindrical member with a ratchet top.

18 is a ratchet ring formed in two halves fitted together with dowel pins 19. The lower side of the ring 18 is formed with a central circular recess 20 to receive the upwardly extending boss of the members 10 85 and 16 and a row of ratchet teeth 21 engaging the teeth 13. A boss 22 projects upwardly from the center of the ratchet ring 18 and a row of ratchet teeth 23 is formed around the boss. 90

24 is a semi-circular stirrup pivotally secured to one of the half sections of the ring 18 and adapted to extend around the other half, a locking screw 25 being threaded through the center thereof to engage the 95 outer side of the encircled member to draw the two halves together.

26 is an orifice extending centrally through the ring 18 from top to bottom. This orifice is formed of polygonal cross 100 section of the ordinary shape of a drill.

27 is a ratchet ring adapted to encircle the boss 22 of the ring 18 having the teeth 28 on the under side adapted to engage the teeth 23 on said ring. 105

29 is an arm extending laterally from the ring 27.

30 is a rod secured to the side of the ring 27 extending diagonally opposite the arm 29 and having an eye 31 at the outer end in 110

which is secured a spiral spring 32. The lower end of the spring 32 is secured in a hole 33 in one end of the bar 1.

34 is a spiral spring secured in a hole 35 in the opposite end of the bar 1 and secured at its upper end to an eye 36 secured to the under side of the arm 29.

37 are bolts extending laterally from the ring 27 and 38 are spiral springs secured to 10 said bolts and extending downwardly, the lower ends being secured to projecting hook members 39 secured to the split sleeve 8. The springs 38 hold the loose ratchet rings in 15 operating engagement the one with the other and the lower ring in engagement with the lower rigid ratchet member on the split sleeve 8.

In the operation of this device, the divided ratchet members are separated as shown in 20 Fig. 3. The shank of the drill is inserted between the halves of the ring 18 and the stirrup member 24 is swung over the top of the drill and the members clamped together. The drill is held from turning in the ring 18 25 owing to the shape of the receiving orifice. The drill shank is then placed in the half hole 11 in the member 10 and the member 16 is then dropped into place, the dovetailed ribs 17 entering the grooves 14. The 30 upper ring 27 is then placed over the boss 22 on the ring 18 and the springs connected as described. A chain 40 connected to the eye 36 in the arm 29 is secured at its opposite end to the upper end of the leg 6 35 holding the springs 32 and 34 slightly in tension. 41 is a strap secured to the outer end of the arm 29. When the device is thus assembled the legs are set in the desired position and the sleeve 8 adjusted to give the 40 desired angle to the drill. The operator secures the loose end of the strap 41 around his leg just below the knee, the length of the strap being adjusted to allow him to stand the required distance from the rig in 45 order to swing his sledge. In swinging the sledge backward for the blow the operator straightens the knee and thus pulls on the strap thereby swinging the arm 29 against the pull of the springs 32 and 34 and 50 through the engagement of the ratchet teeth of the ring 28 and 18 turns the drill a part revolution. As the blow is struck, the knee bends forward thus loosening the strap and the springs 32 and 34 swing the arm back 55 to the original position, the ratchet ring 27 slipping back over the teeth of the ring 18 and the ring 18 being held from return by the engagement of the lower teeth with the teeth 13.

60 The drill may be clamped as tightly as desired but not so tight that it will not drive

freely but the friction is sufficient to grip the drill and lift it clear of the bottom of the hole as the ratchet teeth rise. These teeth are fairly high of pitch so that the 65 head of the drill is lifted free of the loose borings. The action of the device is thus perfectly free.

It will be understood from this description that the drill will be positively held at 70 the desired angle and rotated uniformly and the work will be far more effective than when the drill is manually held.

The device is small and compact and may be readily carried where heavier drilling 75 apparatus is impossible and it may be used extensively not only in surface work but in working drifts and it may be placed where it would be impossible for a man to hold a drill. 80

In setting the device for working in drifts it may be found necessary to dispense with the leg supports. In such cases the bar 1 will be supported in any suitable manner to hold the other members in place. 85

What I claim as my invention is:

1. A drilling rig, comprising, a stand, a stationary member supported on said stand and loosely encircling the drill and having a circular ratchet top, a cylindrical drill 90 holder formed of two half sections adapted to slidably and non-rotatively encircle the drill, a semi-circular stirrup member pivotally secured to one of the half sections of the drill holder and adapted to extend 95 around the other half and carrying a locking screw in the center thereof, a circular ratchet member loosely encircling the drill and engaging the upper ratchet face of the drill holder, and means for holding said 100 ratchet members in operative engagement.

2. A drilling rig, comprising a stand, an upright cylindrical member formed in two halves one of which is secured to said stand and formed with longitudinal dovetail 105 grooves in the flat face and the other half is formed with dovetail ribs adapted to fit said grooves, said cylindrical member having a central circular hole therethrough and ratchet teeth in the top face, a ratchet ring 110 slidably and nonrotatively engaging the drill and having the teeth on its under face engaging the teeth on said cylindrical member, and a ratchet ring adapted to manually rotate said drill holding ring. 115

Signed at the city of Toronto, Ontario, Canada, this 4th day of December, 1913.

AUGUST M. BECKER.
